TORCH IGNITING APPARATUS

Louis V. Aronson, Newark, N. J., assignor to Art Metal Works, Inc., a corporation of New Jersey

Application March 9, 1936, Serial No. 67,760

2 Claims. (Cl. 67—4.1)

5 My invention relates to pyrophoric lighting mechanism of the type comprising a torch which is disposed in the path of a shower of pyrophoric sparks to thereby produce a freely burning flame. My invention has further reference to a novel method of relating or positioning a torch in the path of a shower of pyrophoric sparks so as to effectively and advantageously produce a flame, as aforesaid.

10 My invention has further reference to a pyrophoric lighter constructed and arranged to cause impingement of the pyrophoric sparks upon the actuating torch in a novel manner.

15 Various other objects, advantages and features of my invention will become apparent from the following detailed description.

20 My invention resides in the pyrophoric lighting mechanisms, features, arrangements and combinations of the character hereinafter described and claimed.

25 For an understanding of my invention and for an illustration of some of the many forms thereof, reference is to be had to the accompanying drawings, in which:

25 Figure 1 is a perspective view of pyrophoric lighting mechanism as constructed in accordance with my invention;

30 Fig. 2 is a plan view, with parts removed, of the mechanism shown in Fig. 1;

35 Fig. 3 is a vertical sectional view, partly in elevation, of the mechanism shown in Fig. 1;

40 Fig. 4 is a fragmentary, vertical sectional view, partly in elevation, of the mechanism illustrated in Fig. 3 with some of the parts shown in different positions;

45 Fig. 5 is a transverse sectional view, partly in elevation, and is taken substantially on the line 5—5 of Fig. 3 looking in the direction of the arrows;

50 Fig. 6 is a vertical sectional view, partly in elevation, showing a form of ratchet mechanism;

55 Fig. 7 is a fragmentary, vertical sectional view, partly in elevation, showing a modified form of the invention;

45 Fig. 8 is a horizontal sectional view taken on the line 8—8 of Fig. 7 looking in the direction of the arrows;

50 Fig. 9 is a vertical sectional view, partly in elevation, showing ratchet mechanism utilizable with the form of the invention shown in Figs. 7 and 8;

55 Fig. 10 is a fragmentary vertical sectional view, partly in elevation, showing another form of the invention;

55 Fig. 11 is a transverse, vertical sectional view,

partly in elevation, and is taken on the line 11—11 of Fig. 10 looking in the direction of the arrows;

Fig. 12 is an elevational view, partly in vertical section, of the mechanism shown in Fig. 10; and

Fig. 13 is an elevational view of the mechanism illustrated in Fig. 12 with some of the parts shown in different positions.

Referring to Figs. 1 and 3, F represents a fuel casing with which, in any suitable manner, is associated a main casing M, this main casing being detachably supported, if desired, upon the fuel casing in the manner hereinafter described and both of said casings being formed from suitable sheet metal, or equivalent.

The fuel casing F may be of such suitable configuration as desired. As herein shown, this fuel casing comprises a bottom wall 1 having adhesively secured thereto a layer 2 of felt or the like which is adapted to rest upon any suitable supporting surface. As illustrated, the fuel casing F 10 comprises side wall structure 3 of suitable configuration, the latter being spanned by a top wall 4. This fuel casing, as is customary in the art, is filled with suitable absorbent material 5, such as cotton, and access to the interior of the casing for fuel replenishing purposes may be had by way of an opening in the bottom wall 1, such opening being normally closed by a closure cap 6.

Supported, preferably, in detachable relation on the main casing M is a cover plate 7 which, 30 in the manner hereinafter described, forms a support for the various parts of the lighting mechanism. To this end, the cover plate 7 is provided with a first pair of spaced standards 8, 8a projecting upwardly, said cover plate 7 being also 35 provided with a second pair of standards 9a, 9b projecting downwardly, the standards last noted, in the form of the invention herein shown, being disposed interiorly of the main casing M.

Horizontally supported on the standards 9a, 9b 40 is a fixed pin or member 10 on which a pinion 11 is mounted for free rotatable movement. The pinion 11 comprises a hub 11a extending along the member 10, this hub supporting a wheel 12 which has its outer peripheral face serrated or 45 roughened as indicated. Further, as shown, the member 10 supports a spacing collar 13 which maintains the serrated wheel 12 and associated ratchet parts in assembled relation on the hub 11a as indicated in Fig. 6. As illustrated in Fig. 50 3, the hub 11a of the pinion 11 is provided, on its periphery, with a plurality of pockets 11b having sloping surfaces as shown, each of these pockets receiving a metallic rod 14, or equivalent. As will readily be understood, the rods 14 coact 55

with the interior curved surface of the serrated wheel 12 and the adjacent surfaces of the hub 11a connect these parts together so as to produce rotative movement of the wheel 12 in a counter-clockwise direction, Fig. 3, when the pinion 11 is rotated in the same direction.

The arrangement described immediately above is a preferred arrangement for imparting uni-directional rotative movement to the serrated wheel 12 under the influence of the pinion 11. However, it shall be understood that the invention is not to be thus limited because, if desired, there may be substituted other ratchet arrangements for accomplishing this purpose.

15 Coaxial with the serrated wheel 12 is a pyrophoric element 15 which, in part, projects from a tube 16 anchored in horizontal position in any suitable manner. Thus, for example and as herein shown, said tube 16 may be supported and secured adjacent one of its ends in a depending section 9 of the cover plate 7 and also in an exterior flanged section 7b of said cover plate 7. The tube 16, as shown in Fig. 3, contains a helical spring 17 which, by a cap member 18, is maintained under compression to a suitable degree so as to bias the pyrophoric element 15 into engagement with the serrated wheel 12.

The above described standards 8, 8a horizontally support a pin or member 19 on which an actuating lever 20 and an actuated lever 21 are pivoted. The actuating lever 20 comprises a cam section 20a and a depressed section 20b with which the end of a torch T is adapted to engage as hereinafter described. The actuating lever 20 also comprises an arm 20c which projects downwardly through a slot in the cover plate 7 and terminates interiorly of the main casing M, said arm 20c comprising a stop section 20d. As shown, the lever arm 20c has secured thereto one end of a helical spring 22, the other end of said spring being suitably anchored in a fixed position, as by attachment to a member 23 secured to and projecting downwardly from the tube 16.

40 The actuated lever 21 comprises an arm which extends upwardly through a slot or passage 7c of the cover plate 7, this arm being provided with gear teeth 21a which are disposed in meshing relation with respect to the pinion 11. Further, the actuated lever 21 comprises a latching section 55 21b adapted to engage the adjacent edge of the cover plate 7 at the slot 7c. Still further, the actuated lever 21 comprises a beveled section 21c adapted to be engaged by the cam 20a in the manner hereinafter described. The lever 21 is biased in a clockwise direction by a helical spring 24, one end of which is connected to said lever 21 and the other end of which is connected to the arm 20c of the actuating lever 20.

As shown on the drawings, a casing 25 is secured to the top surface of the cover plate 7 and this casing forms a housing for the standards 8, 8a, the supporting member 19 and those parts of the levers 20, 21 which are disposed above the cover plate 7. As clearly appears from a consideration of Fig. 1, the casing 25 is provided with a slot 25a through which the upper arm of the lever 20 projects so that the depressed section 20b remains continuously on the exterior of said casing 25.

70 The various parts of the herein described mechanism are disclosed in Fig. 3 as occupying their normal respective positions. When thus positioned, the spring 22 maintains the actuating lever 20 in its most advanced counter-clockwise position. At the same time, the spring 24 main-

tains the latching section 21b of the actuated lever 21 in engagement with the cover plate 7 as shown in Fig. 5. Under such conditions, the various parts are in condition for manual operation by the torch T.

5 This torch may be of suitable character as desired. Thus, for example, said torch may be as disclosed in my pending application Serial No. 37,645, filed August 24, 1935 and, if so, the torch comprises a handle section 26 from which depends a sleeve 27 utilizable as an enclosure for a wick 28 and a rod 29, the lower end of said wick and rod projecting from the sleeve 27 as shown in Figs. 3 and 4.

10 As described in my pending application Serial No. 30,063, filed July 6, 1935 and as illustrated in Figs. 1, 3 and 4, a tubular member 30 is anchored in a nut member or bushing 31 which is suitably secured to the top wall 4 of the fuel casing F, the tubular member 30, therefore, providing a passage which communicates with the interior of said fuel casing F. The cover plate 7, when positioned on the main casing M as shown in Figs. 1-5 inclusive, is provided with an opening through which the tubular member 30 freely 20 extends, the upper end of said tubular member 30 25 being exteriorly threaded for the reception of a clamping nut 32.

15 In the same general manner as described in my aforesaid pending application Serial No. 30,063, filed July 6, 1935, the main casing M may be disposed in its proper position on the fuel casing F whereupon the cover plate 7 and the operating mechanism carried thereby are disposed upon the top surface of said main casing M. 35 When these various parts have been properly arranged in assembled relation, the upper end of said tubular member 30 extends above the cover plate 7 and, accordingly, the nut 32 may be threaded to said tubular member 30 to thereby 40 secure the main casing M and the cover plate 7 in assembled relation with respect to each other and with respect to the fuel casing F.

45 As shown particularly in Fig. 3, the torch T is disposed in its normal position as extending downwardly through the tubular member 30. When thus positioned, the lower end of the torch wick 28 is disposed within the fuel casing F so as to be in fuel-absorbing relation with respect to the fuel contained therein. Preferably, said lower 50 end of the torch wick is received within a tubular structure, not shown, which extends vertically within the fuel casing as more fully described in my aforesaid pending application Serial No. 37,645, filed August 24, 1935. 55

When the mechanism of Figs. 1-6 inclusive is to be operated, the torch T is withdrawn from its normal seating position as shown in Fig. 3 and the lower end of the torch rod 29 is disposed in engagement with the section 20b of the actuating lever 20. Then, by the application of downward pressure, said actuating lever 20 is moved in a clockwise direction, Fig. 3, with resultant storage of energy in the springs 22 and 24. Even though energy is thus stored in the spring 24, 65 the actuated lever 21, at this time, does not move clockwise, Fig. 3, under the influence of said stored energy because the latching section 21b of said lever 21 is in engagement with the adjacent edge of the cover plate 7, Fig. 5. During 70 continued movement of the actuating lever 20 in a clockwise direction, Fig. 3, the cam section 20a thereof engages the beveled section 21c of the actuated lever 21 to thereby move said lever 21 slightly in a lateral direction so as to disengage 75

the latching section 21b from said cover plate 7. When this happens, the energized spring 24 becomes effective to suddenly swing the actuated lever 21 in a clockwise direction, Fig. 3, with the 5 result that the gear teeth 21a impart a step of rotative movement in a counter-clockwise direction, Fig. 3, to the pinion 11. By the described ratchet mechanism, the pinion 11 causes the serrated wheel 12 to move therewith in a counter- 10 clockwise direction, Fig. 3, to thereby produce a shower of sparks which are projected upwardly through the slot 1c of the cover plate 7. As clearly appears from a consideration of Fig. 4, these sparks are projected in the general direction 15 of the longitudinal axis of the torch whereby the charge of fuel carried by the lower exposed end of the torch wick 28 is ignited in an efficient manner to produce a freely burning flame.

The torch T, immediately after ignition therefore, is removed from the section 20b of the actuating lever 20 so as to be used in a desired manner for ignition purposes. Immediately thereafter, the various parts are automatically returned to their respective normal positions under the influence of the spring 22. That is, as clearly appears, this spring 22 rotates the lever 20 in a counter-clockwise direction from the position thereof shown in Fig. 4. In so doing, the lateral section 20d of said lever 20 engages with and 20 causes the actuated lever 21 to move in a counter-clockwise direction, Fig. 4, until said lever 21 reaches its normal position as shown in Fig. 5 wherein the latching section 21b of the lever 21 is in engagement with the cover plate 7. At this 25 time, the lever 20 comes into engagement with a suitable stop surface such as is presented by a surface of the housing 25 and, when this occurs, the various parts are in their normal respective positions and in condition for subsequent operation when desired.

The form of the invention illustrated in Figs. 7, 8 and 9 is generally the same as that described above in connection with Figs. 1-6 inclusive. However, the mechanism illustrated in said Figs. 45 7, 8 and 9 embodies an arrangement of a different character from that heretofore discussed for imparting movement to the serrated wheel 12.

Thus, as shown, movement of the actuated lever 21 of Fig. 7 is resisted solely by the pressure 50 exerted on the serrated wheel 12 by the pyrophoric element 15 under the influence of the spring 17. In other words, the arrangement of Figs. 7, 8 and 9 does not include a latching section 21b, or equivalent, for temporarily restraining movement of said actuated lever 21.

Accordingly, when the actuating lever 20 of Fig. 7 is depressed by the torch to effect clockwise movement thereof, the section 20d of said lever 20 recedes from the actuated lever 21 and, during such action, energy is stored in the spring 24. However, at this time, movement of the serrated wheel 12 does not occur by reason of the braking effect applied thereto by the spring 17. Eventually, during continued movement of the lever 20 65 in a clockwise direction, Fig. 7, the upper section thereof comes into engagement with the upper end of the lever 21 to impart slight movement thereto. In response to such impulse of movement, the braking effect of the spring 17 is overcome and the energized spring 24 becomes effective to swing the lever 21 with a snapping motion in a clockwise direction, Fig. 7, whereby a step of rotative movement is imparted to the serrated wheel 12 to thereby project sparks upwardly into engagement with the torch which is now resting

on the depressed section 20b of the lever 20 whereby the charge of fuel carried by the torch wick is ignited.

Upon removal of the torch T from the lever 20 shown in Fig. 7, the various parts automatically return to their normal respective positions, this being accomplished under control of the spring 22. Thus, in the general manner heretofore described, the lateral section 20d of the actuating lever 20 engages the lever 21 so that both of the 10 levers 20 and 21 move in unison under the control of said spring 22 whereby the parts return to normal position as shown in Fig. 7. During this operation, the actuated lever 21 moves in a counter-clockwise direction, Fig. 7, to thereby 15 rotate the pinion 11 in a clockwise direction, Fig. 7. Due to the presence of the described ratchet arrangement, the serrated wheel 12 remains stationary during the last described movement of the lever 21.

The form of my invention illustrated in Figs. 7 and 8 comprises a modified form of support for the pinion 11, the serrated wheel 12 and the parts directly associated therewith. Thus, as shown, these various parts are supported by a bracket 25 arm 9c which is secured directly to the cover plate 7. It shall be understood, however, that the supporting arrangement of Fig. 6 may be employed with the mechanism shown in Fig. 7 or, if desired, other forms of supporting mechanism may be utilized if desired.

It will be understood that the extent to which the spring 17 biases the pyrophoric element 15 into engagement with the serrated wheel 12 is dependent upon the degree to which said spring 35 17 is compressed by the nut 18. Therefore, with respect to Fig. 7, the spring 17 in conjunction with the pyrophoric element 15 may exert only a slight pressure on the serrated wheel 12. If so, the action may be somewhat different than described 40 immediately above since, as will be understood, the lever 21 of Fig. 7 may be released before it is engaged by the lever 20. That is, said lever 21 of Fig. 7 will be released to rotate the pinion 11 as soon as the spring 22 overcomes the spring 24.

Referring to the form of my invention illustrated in Figs. 10-13 inclusive, the main casing M is shown as having a cover plate 40 secured thereto by a clamping nut 41. Depending from the cover plate 40 is a hollow housing 42 with which a fixed frame member 43 is associated. This frame member 43 serves as a support for a horizontal pin or member 44 on which a pinion 45 is supported for free rotatable movement, this pinion comprising a hub 45a on which a serrated wheel 46 is journalled, a suitable ratchet arrangement comprising the rods 47, or equivalent, being utilized for clutching the wheel 46 to the pinion 45. As shown in Fig. 11, a spacing washer 48 maintains these various parts in assembled relation. Coactable with the serrated wheel 46 is a pyrophoric element 49 which projects from a tube 50 anchored in the aforesaid frame member 43. As well understood in the art, the pyrophoric element 49 is biased into engagement with 55 the serrated wheel 46 by a spring, not shown.

The aforesaid cover plate 40 is provided with an opening which is aligned with the space defined by the housing 42. Slidable through this opening into said housing 42 is a member 51 having, 70 above said cover plate 40, a laterally extending member 52 provided with a depressed section 52a adapted to receive the lower end of the actuating torch, said member 52 also comprising an actuating section 52b utilizable as hereinafter de- 75

scribed. The member 51 is biased in an upward direction in any suitable manner, as by a spring 53 which is spirally disposed therearound.

Telescopically received in the lower end of the member 51 is a rod 54 having a spiral spring 55 disposed therearound, this spring being compressed by the member 51 in the manner herein-after described. The rod 44 seats upon and is secured to the angular end 56a of a member 56 which extends upwardly in flush engagement with one flat face of the housing 42. The member 56 is provided with upper and lower elongated slots 57, the upper slot 57 being aligned, when the member 56 is in its upper position, with a slot 57a in the adjacent flat face of the housing 42. Through the upper slots 57 and 57a, a screw 57b is threaded into the member 51. Through the lower slot 57, a screw 57c is threaded into the housing 42. As clearly shown in Fig. 10, the member 56 comprises a projecting section 56b equipped with rack teeth for engagement with the aforesaid pinion 45.

In accordance with the invention, a lever 58 is pivoted at 59 to one face of the housing 42, this lever 58 comprising a section 58a extending upwardly through the cover plate 40 so as to be engageable with the actuating section 52b of the member 52. The lever 58 further comprises a downwardly extending section 58b adapted, when biased to the position shown in Fig. 12 by the spring 59, to engage a lateral section 56c of the member 56.

The various parts are shown in Fig. 10 as occupying their respective normal positions. When the mechanism is to be actuated, the torch T is removed from its seat and the lower end of said torch is engaged with the depressed section 52a of the member 52. Thereupon, by the application of downward pressure, said torch T moves the member 51 downwardly and stores energy in the springs 53 and 55. During such initial downward movement of the member 51, the member 56 remains stationary by reason of the fact that the lateral section 56c thereof is engaged by the latching section 58b of the lever 58. Eventually, as downward movement of the member 52 continues, the actuating section 52b thereof comes into engagement with the section 58a of the lever 58 whereby said lever is swung in a counter-clockwise direction, Fig. 12, to thereby release the lever latching section 58b from the extension 56c of the member 56. As soon as this action has been effected, the spring 55 becomes free to expand and, in so doing, the member 56 is moved downwardly with a snapping action to thereby rotate the pinion 45 in a counter-clockwise direction, Fig. 10. By action of the described clutching mechanism, the serrated wheel 46 partakes of similar counter-clockwise movement, Fig. 10, whereby a shower of sparks is directed upwardly through an opening 40a in the cover plate 40. These sparks engage and ignite the charge of fuel carried by the wick at the lower

end of the torch T as the latter rests upon the member 52. When the torch has thus been ignited, it may be removed from said member 52 and utilized as desired.

As soon as the torch T is thus removed from the member 52, the spring 53 becomes effective to restore the various parts to their normal positions. In so doing, the member 51, under the control of the spring 53, is elevated to the position shown in Figs. 10, 11 and 12, said member 51, through the upper screw 57b, carrying the member 56 and rod 54 upwardly therewith. When the member 56 reaches its upper position, the lever 58 swings clockwise from the position thereof shown in Fig. 13 so as to again come into engagement with the section 56c of said member 56. At this time, the various parts are again in their normal positions in condition for subsequent operation.

While the invention has been described with respect to certain particular preferred examples which give satisfactory results, it will be understood by those skilled in the art after understanding the invention, that various changes and modifications may be made without departing from the spirit and scope of the invention and it is intended therefore in the appended claims to cover all such changes and modifications.

What is claimed as new and desired to be secured by Letters Patent is:

1. Pyrophoric lighting mechanism comprising a fuel receptacle, a sparking device including a rotatable wheel, a pyrophoric metal member bearing against said wheel, means comprising a movable actuating member for operating said sparking device, and a manually actuatable torch engageable with said actuating member to move the same and thereby produce a shower of sparks which move along a path tangentially related to said wheel, said torch comprising a wick which is held by said actuating member for movement substantially longitudinally of said path of the sparks and substantially in the opposite direction taken by said sparks.

2. Pyrophoric lighting mechanism comprising a casing having a top wall, a sparking device interiorly of said casing, an actuating member disposed above said top wall, means connecting said sparking device and said actuating member, a torch engageable with said actuating member to move the same with respect to said top wall, said torch carrying a charge of fuel which is ignited by sparks projected upwardly along a path extending through an opening in said top wall, said torch and the charge of fuel carried thereby moving substantially longitudinally of said path of the sparks and substantially in the opposite direction taken by said sparks, and a delayed-action spring in which energy is stored during initial movement of said actuating member for actuating said sparking device.

LOUIS V. ARONSON.
